UNITED STATES PATENT OFFICE.

THOMAS J. GORDON, OF OLATHE, KANSAS.

BURGLAR-ALARM.

SPECIFICATION forming part of Letters Patent No. 408,010, dated July 30, 1889.

Application filed April 13, 1889. Serial No. 307,100. (No model.)

To all whom it may concern:

Be it known that I, THOMAS J. GORDON, a citizen of the United States, and a resident of Olathe, in the county of Johnson and State of 5 Kansas, have invented certain new and useful Improvements in Burglar-Alarms; and I do declare the following to be a full, clear, and exact description of the invention, such as will enable others skilled in the art to 10 to which it appertains to make and use the same, reference being had to the accompanying drawings, and to letters of reference marked thereon, which form a part of this specification.

15 Figure 1 of the drawings is a representation of this invention, and is a plan view of the alarm mechanism. Fig. 2 is a section taken where the broken line $x\ x$ is marked on Fig. 1. Fig. 3 is a section taken where the broken line $y\ y$ is marked on Fig. 1. Fig. 4 is a section taken where the broken line $z\ z$ is marked on Fig. 1. Figs. 5 and 6 show the manner of arranging the wires connected with the alarm for windows and doors.

25 This invention relates to certain improvements in burglar-alarms for dwellings and stores; and it consists of the novel combination and their construction of parts, as will more fully appear from the following description.

In carrying out my invention I employ an alarm mechanism, which I will describe as follows: Within an inclosing-case A, secured to a suitable base a for putting it in position, 35 is arranged a clock mechanism, including an escapement b and a hammer b' , which is arranged to strike a gong b^2 , suitably disposed upon the base or bracket a .

C is a transversely or horizontally arranged 40 spring-pressed plate-like bar adapted to have a sliding movement and to project through the side of the case A, its actuating end being provided with a knob c . This bar or plate C has near one end a shoulder c' , which is 45 adapted to rest against the hammer-rod and lock the striker or hammer in position, or hold it away from the gong when desired. This bar or plate has also a slot or aperture c^2 therein near its other end, the purpose of 50 which will presently appear.

D is a spring-pressed locking-bar arranged

at right angles to the bar or plate C, and having in its outer projecting or upper end an aperture d for the convenient connection therewith of the wire e , through which connection, as presently explained, is effected with the windows and street or outside doors. The inner or opposite end of the locking bar or rod D is adapted to engage or enter the aperture or slot c^2 of the bar or plate C when 55 it is desired to lock the said plate or bar C in position, the latter being pressed inward until its aperture or slot coincides with the inner end of the bar or rod D, permitting the springing thereinto of the rod or bar D. 60

Simultaneously with the inward movement of the bar or plate C it will be seen that by the contact of its shoulder c' with the hammer-rod the hammer b' will be moved away from the gong b^2 and will be locked in that 65 position, preventing the ringing or sounding of the latter. Arranged crosswise of the locking rod or bar D, and having one end extending beyond the left-hand side of the inclosing-case A, is a rotary rod E, which has a knob 70 upon its projecting end for convenient manipulation, and a transverse pin e' through it, adapted to engage a projection or stop e^2 upon the inside of the case A, to limit its rotation when turned by the hand applied to its 75 knob. The rotary rod E has opposite the bar or rod D a notch or recess e^3 , and the rod or bar D has a notch or recess e^4 coincident with the rod E.

It will be noticed that with the notch or recess e^3 of rod E facing the rod D the latter is 80 capable of movement, and when the rod E is rotated or turned, so as to cause the said notch or recess to face upward, bringing the convexity of the rod E into the notch or recess 85 e^4 of the bar or rod D, the latter is incapable of movement, therefore preventing any possibility of the accidental disconnection of the locking bar or rod D from the plate or bar C when holding the gong or bell hammer out of 90 action or in its locked position.

The spring of the clock mechanism is wound by the application of the key to the shaft f , as will be readily understood, turning the key, of course, to the left. The wire e is 100 passed along near the ceiling of the room over pulleys g , suitably disposed, and at points

over the windows and outer doors it is severed and connected to rings g' . From the rings g' extend downward over other pulleys h suitably-disposed branch wires i , which are carried 5 under the lower pulleys h' and upward next to the windows and connected in any suitable way to the tops of the lower sashes. The attempted raising or movement of the sashes, it will thus be seen, would set off the alarm 10 and give the required warning or notice.

In the application of the wires to the doors the connection is somewhat different, the branch wires i being through an eye or pulley i' and having attached to its end a drop-hook 15 i^2 , which is adapted to engage with a fixed projection or catch i^3 upon the inside of the door at its extreme upper left-hand corner or at the opening side. From this it is obvious 20 that the attempted opening of the door would send in an alarm. In order, however, to permit the occupant of the house to open the door without disturbing the alarm, I connect with the drop-hook i^2 a cord j , which is passed over a pulley j' , slightly elevated with relation 25 to the top edge of the door, and so arranged as to permit the cord j to extend down closely to the joint, whereby it may be easily reached and manipulated with the door slightly 30 opened by the hand placed through the opening thus furnished. A ring j^3 is applied to the lower end of said cord j , which is slipped upon a catch or hook k , projecting from the door-casing.

It will be observed that the relation of the 35 hook i^2 with the catch i^3 is such that a limited amount of movement is permissible between the same previous to engagement, in order to allow of the slight opening of the door, for the purpose presently disclosed.

40 It will be seen that while any one ignorant of the presence of the detaching drop-hook contrivance just described attempting an entrance would cause the alarm to be sounded, yet by the inmate or occupant of 45 the dwelling or house reaching through the small opening furnished by slightly opening the door, as above stated, and pulling upon the cord j , the drop-hook will be removed sidewise or laterally from the catch or 50 projection i^3 upon the door, and catching or slipping the ring j^3 upon the catch or projection k the door can be opened in the usual manner and admission obtained without interference with the alarm mechanism.

It will be understood that my invention 55 is equally applicable to barns, stables, or other outhouses.

Having described this invention, what I claim, and desire to secure by Letters Patent, 60

1. The burglar-alarm having the clock mechanism, the bell or gong hammer and gong or bell, in combination with the plate or bar having a shoulder acting upon the hammer, and a slot or aperture, the spring-pressed locking bar or rod engaging with the 65 said slot or aperture and having connection with the windows and doors of a dwelling, &c., substantially as specified.

2. The combination, with the spring-pressed 70 locking-rod engaging a slot or aperture in the spring-pressed plate or bar engaging with the bell or gong hammer rod, of the rotary rod or bar having a notch or recess facing the aforesaid locking-rod, substantially as specified. 75

3. The combination, with the spring-pressed locking-rod engaging a slot or aperture in the spring-pressed hammer-locking bar or plate, of the rotary rod having a notch or 80 recess facing the aforesaid locking-rod, said latter-referred-to rod also having a notch or recess receiving the convex or rounded portion of the rotary rod, substantially as set forth. 85

4. In a burglar-alarm, the combination, with the alarm mechanism, comprising the spring-pressed locking-rod, the spring-pressed slotted plate or bar engaged by said rod, the bell or hammer rod engaged by said plate, 90 and the rotary rod or bar having a notch or recess facing said locking-rod, and the alarm-transmitting wire or medium, of the branch wire or its equivalent having a drop-hook 95 engaging a catch or projection on the door and having connected to it a manipulating-cord, or its equivalent, passing over a suitably-disposed pulley, and means for holding the drop-hook away from the door, substantially as shown and described. 100

In testimony whereof I affix my signature in presence of two witnesses.

THOMAS J. GORDON.
